UNITED STATES PATENT OFFICE.

ARTHUR K. MILLER, OF WATERBURY, CONNECTICUT.

ACETYLENE-GAS LAMP.

SPECIFICATION forming part of Letters Patent No. 650,854, dated June 5, 1900.

Application filed January 13, 1900. Serial No. 1,262. (No model.)

To all whom it may concern:

Be it known that I, ARTHUR K. MILLER, a citizen of the United States, residing at Waterbury, county of New Haven, State of Connecticut, have invented certain new and useful Improvements in Acetylene-Gas Lamps, of which the following is a specification.

One object of my invention is to provide improved means for feeding water to calcic carbid, to the end that the feeding of water can be conveniently regulated in accordance with the quantity of gas to be evolved.

Another object of the invention is to provide an improved construction of acetylene-gas lamp particularly adapted for use on vehicles.

The invention also consists in the novel details of improvement that will be more fully hereinafter set forth and then pointed out in the claims.

Reference is to be had to the accompanying drawings, forming part hereof, wherein—

Figure 1 is a plan view of a lamp embodying my improvements, the cover being removed. Fig. 2 is a partly-sectional side elevation thereof, and Fig. 3 is a vertical cross-section on the plane of the line 3 3 in Fig. 2.

In the accompanying drawings, in which similar numerals of reference indicate corresponding parts in the several views, 1 indicates a lamp-body, which is shown provided with three main compartments 2 3 4. In the arrangement shown these compartments are formed by means of a horizontally-disposed partition 5, secured to the walls of the body, and a vertically-disposed partition 6, from which a top wall 7 extends to and is connected with the walls of the body 1, (see Figs. 1 and 2,) and thus the body and partitions 5 6 40 form the chamber 2, the body, with the partitions 5 6 and wall 7, form the chamber 3, and the body and partition 5 form the chamber 4 beneath the chambers 2 and 3. The chamber 2 contains a burner 8, that communicates with chamber 4, and thus chamber 2 constitutes a fire-chamber. The chamber 3 constitutes a water-chamber and the chamber 4 a gas-generating chamber. The wall 7 is shown provided with a screw-cap 9 for the admission of water.

10 is a perforated cover or cap on body 1, that forms the cover of chamber 2.

The front wall of chamber 2 has an opening protected by a glass or other suitable protector 11, which in Fig. 1 is shown curved to correspond to the curve of body 1 and lies against the inner surface of the front wall of chamber 2, and 12 is a reflector, which extends across chamber 2 at the back part of the same behind burner 8 and has its ends bent or curved forwardly, so as to engage the adjacent vertical edges of protector 11, and the reflector 12 preferably has a central depression 12^a, which may be oval, that bears against the partition 6, and thus the parts 11 and 12 are braced against each other and held firmly within chamber 2. The parts 11 and 12 are inserted in chamber 2 by sliding them in through the top opening when the cover or cap 10 is removed and they are held down by the cover or cap.

13 is a conduit located within the water-chamber 3 and having one end leading through an opening in the bottom partition 5 thereof and its other end opening through the outer wall of said chamber. (See Fig. 3.) This conduit is provided with a valve 14, shown in the form of a screw or threaded stem meshing in threads in the conduit and having a tapering end 14^a to fit against a seat in conduit 13, an enlarged portion 13^a of said conduit being in line with a reduced portion of the valve-stem, an aperture 13^b in the wall of the conduit permitting water to pass from chamber 3 into the conduit. The valve 14 is shown provided with a head 14^b for operating it, and packing 15 serves to make a tight joint. The inner end of the conduit 13 leads to a hollow hanger or support 16, that is secured to the partition 5 and depends therefrom into chamber 4, said hanger being provided with internal screw-threads that receive corresponding threads on a depending tube 17. Said hanger is shown provided with a shoulder 16^a, against which a cup or the like 18 rests, the upper edges of said cup resting against the partition 5, and thus forming a chamber to contain a suitable gas-filter, one or more apertures 18^a in the cup 18 permitting gas to enter the same. The burner 8 leads to the chamber formed by the cup 18 and the partition 5. (See Fig. 2.) The hanger 16 also has external threads that mesh with internal threads at the upper end

of a chamber 19, that has a closed lower end, the tube 17 projecting into said chamber to a point above the lower end of the latter, thereby forming a water-receptacle or well 20 between the lower ends of said parts. (See Fig. 3.) The chamber 19 is shown screwed against the bottom of cup 18, and thus, in conjunction with the support 16, holds the latter pressed against the partition 5. 21 is an absorbent material, such as a fibrous wick, surrounding tube 17 and located within chamber 19, the lower end of the wicking leading to the water-receptacle or well 20 but not to the bottom of chamber 19. The chamber 19 near its upper end is provided with one or more ports 20^a for the escape of water.

When the valve 14 is opened, water passes through conduit 15 and tube 17 into the receptacle or well 20 in chamber 19 and engages the wick 21, and is drawn up through the latter by capillary action, escapes through the port 20^a, and trickles down the exterior of chamber 19. The construction is such as to provide a uniform water feed, or one that is not affected either by changing weight of water above the feed-tube or the pressure of gas at the outlet, and an alternating pressure between the gas and water is prevented. Thus the small well of water is at the lower part of the lamp, while the reservoir is above, and the feeding action of the water is by capillary attraction upwardly through the wick to the port 16^a, discharging above the carbid. Chamber 19 projects in calcic carbid to deliver water thereto. The chamber 19 is shown projecting through an aperture in the cover 22 of a carbid-receptacle 23, that is located within the lower end of chamber 4, and held in place by a cap 24, attached to body 1 by any suitable means, such as a pin and slot 25 26, whereby the cap can be removed. To make a gas-tight fit, the receptacle 23 is shown provided with a flange 23^a, that is alined with the end of body 1, between which a gasket 25 is located, and the end of body 1 is shown bent inwardly to form a somewhat broad seat for the gasket to rest against.

I do not limit my invention to the details of construction shown and described, as they may be varied without departing from the spirit thereof.

Having now described my invention, what I claim is—

55 1. The combination of a chamber having a closed lower end, with fibrous material within said chamber and located above the lower end of the same, forming a well or receptacle, said chamber having a port above the lower end, and means for leading water into the well at the lower end of the chamber below the fibrous material, substantially as described.

60 2. The combination of a tube, a fibrous material surrounding the same, and a chamber surrounding said material and having a closed end forming a water-receptacle or well be-

yond said fibrous material, said chamber having a port above the well, substantially as described.

70 3. The combination of a support, a tube depending therefrom, fibrous material surrounding the tube, a chamber depending from said support and having a closed lower end that extends beyond the fibrous material forming a water-receptacle, said chamber having a port in its wall for the passage of water from the fibrous material, substantially as described.

4. The combination of a partition or wall, a support, a cup surrounding said support, a tube depending from said support, fibrous material surrounding said tube, and a chamber surrounding said material and having its lower end closed and forming a water-receptacle or well below said material, said chamber having an outlet, substantially as described.

80 5. The combination of a wall, a support depending therefrom, a cup surrounding said support, a tube depending from said support, a fibrous material surrounding said tube, a chamber surrounding said material and having its lower end closed and forming a water-receptacle or well below said material, said chamber having an outlet, a conduit leading to said support, and a valve for controlling the passage of water to said conduit, substantially as described.

90 6. The combination of a chamber forming a well or receptacle for water and provided with an outlet above the latter, fibrous material located between the well or receptacle and the outlet, means for supplying said chamber with water, and a carbide-retainer, the well or receptacle being located within the carbide to be subjected to the heat generated by the carbide, substantially as described.

100 7. The combination of a body having a horizontal partition connected with its walls, a vertical partition, a horizontal partition connecting the vertical partition with the walls of the body, said partitions and walls forming a water-chamber, a flame-chamber, and a gas-chamber below the water-chamber, means 110 for holding carbide in the gas-chamber, means for supplying carbide with water, and a burner in the flame-chamber communicating with the gas-chamber, substantially as described.

115 8. In a lamp the combination of a body having a water-chamber at its upper portion, a tube depending therefrom, a valve in the water-chamber communicating with said tube, a chamber below said tube forming a well at the lower portion of the lamp, said chamber having a port in its wall, and a wick above said well to feed water upwardly therefrom to discharge at the upper part of the gas-chamber above the carbide, substantially as described.

120 9. The combination of a body having interior partitions forming a fire-chamber, a water-chamber, and a gas-chamber, means for holding carbide in the gas-chamber, a con-

duit within the water-chamber having an opening and a valve, a tube in the gas-chamber communicating with said conduit, fibrous material surrounding said tube, and a chamber surrounding said fibrous material and having its lower end extending below the fibrous material forming a water-receptacle, said

chamber having a port, and means for retaining carbide in the gas-chamber, substantially as described.

A. K. MILLER.
